UNITED STATES PATENT OFFICE

1,987,500

CARTON SEALING MACHINE

Charles H. Wild, Baltimore, Md., assignor to Burt
Machine Company, Incorporated, Baltimore,
Md., a corporation of Maryland

Application August 15, 1934, Serial No. 739,959

43 Claims. (Cl. 53—6)

This invention has for its object an improved means in a carton-sealing apparatus for sealing a carton received in the machine with its bottom flaps closed unsealed; and it provides mechanism 5 to permit the carton to be successively and automatically admitted to the operation thereupon of devices for unfolding the flaps, for folding the flaps back into closed position, and for subjecting the closed flap to pressure for a sufficient 10 length of time for the adhesive to become set to a sufficient degree to permit the carton to be handled without danger of opening.

The above sealing of a carton broadly is old, and is usually accomplished by unfolding the 15 outer flaps, applying an adhesive thereunto, re-folding the same and pressing the re-folded flaps onto the unpasted inner flaps so that the same may adhere thereto.

An attempt has been made to apply the adhesive to the inner flaps while the outer flaps are 20 partially folded outward to permit the applying of the adhesive. It has been found difficult to properly support the contents of the carton, and many obstacles have been encountered which 25 prevented the practical operation of the efforts along this line.

The applicant has entirely overcome the difficulties as above set forth.

The usual way to support the contents of the 30 carton is by means of the lower flap resting upon supports, the supports preventing the application of the adhesive to the flaps, thus necessitating the pasting of the outer out-turned flaps, and this is almost the universal custom. The applicant has also overcome this difficulty.

For certain classes of work, it is very desirable to paste both inner and outer flaps so that the pasted surface of each may become adjacent and adhere when folded.

40 Applicant has devised an improved means for causing a skip in the application of adhesive to the surface of a flap. He has devised means for adjusting the space of skip while the machine is in operation, and also means whereby the desired 45 extent of the skip may be maintained and at a particular predetermined point with relation to the carton operated upon, whereby the skip may clear the contents or such parts of the carton as may be desirable.

50 A further object of this invention is the distinct segregation of the pasting and folding apparatus from the pressing and its feeding apparatus, providing an intermediate means for controlling the transfer of the carton from the pasting-fold- 55 ing apparatus to the sealing apparatus for the

purpose of inspection and the removal of defective cartons.

A further object of this invention is the providing of improved means for sealing the flaps of cartons by progressively increasing the pressure from near the outer edge of the flaps to the center edge where most pressure is desired in maintaining a perfect seal, and continuing this condition for sufficient time to permit the adhesive to become fixed.

10 A further object of my invention is the providing of automatic adjusting means to exert a maximum desired pressure at a predetermined point in the sealing of the carton, and means for adjusting said pressure to conform to the carton 15 being operated upon.

In addition to the general broad scheme, the objects of this invention are further details of a novel character for carrying out the objects herein enumerated.

20 The adhesive-applying device of a plural character parallelly situated for applying adhesive to the inner flaps, and also to the outer flaps as may be desired, is broadly new, so far as applicant knows, the same not having been attempted in 25 the art heretofore.

Novel features will be found in the adhesive-applying device, in the sustaining devices for the contents of the carton, for the control of the skip space of the surface upon which the adhesive is applied, the relative change of position of said space, the control of the admission and delivery of the cartons to the various elements, and many other details which will hereinafter appear.

30 With the foregoing and other objects in view, my invention consists of the novel construction, combination and arrangement of parts as hereinabove specifically described and illustrated in the accompanying drawings, wherein is shown the preferred embodiment of my invention, but it is understood that changes, variations and modifications can be resorted to which come within the scope of the claims hereunto appended.

45 In the drawings of the herein-described embodiment of my invention, Figure 1 is a side view in elevation of my carton closing and sealing machine, illustrating the initial feeding mechanism thereof; Fig. 2 is a continuation of Fig. 1, 50 illustrating the pasting portion of my machine, together with means for enabling the extracting of a carton from the guideways of the machine; this latter feature is particularly shown in Fig. 3, which is a continuation of Fig. 2, and 55

is an independent means for delivering the carton from the pasting and flap-closing section of the machine to the presser-roll portion of the machine, which allows for the pressing down of the previously pasted and closed flaps of the carton; Fig. 4 is a continuation of Fig. 3 of the delivery end of the machine, illustrating in side elevation the presser-roll structure as well as the variable speed drive for this section of the machine.

Fig. 5 is a fragmentary plan of the initial feed portion of the machine; Fig. 6 is a continuation of the plan view shown in Fig. 5, illustrating means for delivering cartons in predetermined spaced relation to that section of the machine for initially opening the lower flaps of the carton; Fig. 7 is a continuation of the plan view of the machine as illustrated in Fig. 6, disclosing a fragmentary portion of the lower flap-opening means together with the pasting mechanism for applying paste to the bottom flaps of the carton. I will here call attention to the fact that the carton in its path through the machine in the feeding, opening, closing and pressing, is substantially on the same plane, thus preventing any undue displacement of the contents of the carton. The view in Fig. 7 also illustrates a fragmentary portion of the means for initially closing the bottom flap members after the pasting of the flaps; Fig. 8 is a fragmentary plan view of that portion of the machine illustrating the means for finally closing the flaps of the carton and the delivery to the independent conveying means, the full line in the drawings showing the top flap closing means; Fig. 9 is a plan view of that portion of the machine shown in Fig. 8; Fig. 10 is an enlarged fragmentary sectional view in elevation, taken through 10—10 of Fig. 7, looking in the direction of the arrows; Fig. 11 is a fragmentary plan view illustrating a presser-roll means for increasing pressure towards the center portion of the carton, the same allowing for the application of increasing pressure to the top flaps of the cartons after the same have been pasted and closed; Fig. 12 is a fragmentary sectional view in elevation, taken on the line 12—12 of Fig. 11, looking in the direction of the arrows; Fig. 13 is a fragmentary plan view similar to that shown in Fig. 11 of the drawings, illustrating a different type of presser-roll structure, whereby a greater variation of irregularity in the surface of the carton particularly towards the center may be compensated for; Fig. 14 is a side elevation of the appliance shown in Fig. 13; Fig. 15 is an enlarged sectional view in elevation, taken on line 15—15 of Fig. 13, looking in the direction of the arrows; Fig. 16 is a transverse sectional view in elevation, taken on the lines 16—16 of Fig. 7, looking in the direction of the arrows, and illustrating adjustable means for varying the position of the carton guideways and the carton-supporting grid structure; Fig. 17 is a fragmentary end view of the actuating mechanism for the carton spacing means, located near the feed end of the machine.

Fig. 18 is a view in elevation of the adjustable female cam member and its follower, which allows for controlling the timing of the operative and inoperative positions of the bottom pasting rollers in relation to the traverse of the carton; Fig. 19 is a sectional view taken on the line 19—19 of Fig. 18, looking in the direction of the arrows; Fig. 20 is a view in elevation of the adjustable male cam member and its follower, which has a

function for operating the upper pasting rollers similar to that of the female cam member as shown in Fig. 18; Fig. 21 is a sectional view taken on the line 21—21 of Fig. 20, looking in the direction of the arrows.

Fig. 22 is a fragmentary front elevation of one of the adjustable roller mountings as used with the male and female cam members shown in Figs. 18 and 20; Fig. 23 is a plan view of the same; Fig. 24 is a modified form of a female adjustable cam member, which allows for ready and convenient adjustment of the same as to the mechanical function of the pasting rollers during the operation of the machine, the function of this cam member being similar to that set out in describing Figures 18 to 20 of the drawings; Fig. 25 is a sectional view taken on the line 25—25 of Fig. 24, looking in the direction of the arrows.

Fig. 26 is a fragmentary elevation of the upper portion of a filled carton, the same being shown in relation to the upper pasting rolls during the simultaneous pasting operation of both the inner and outer carton flap members.

Fig. 27 is a sectional view in elevation, taken through 27—27 of Fig. 10, having, however, a filled carton in position between the pasting rolls and the outer flaps protected from the pasting rolls in the operation, whereby only the inner flaps are pasted, as may be desired, and particularly shows the guard members 46 for protecting the outer flaps from receiving the paste. The better to understand this feature, the pasting of the outer and inner flap is illustrated in Fig. 28, the carton moving through the machine in the direction of the arrow. Fig. 29 is a view somewhat similar to that shown in Fig. 28, illustrating the protection of the outer flaps from being pasted, as more particularly illustrated in the sectional view 27.

Fig. 30 is an enlarged view particularly showing the operation of the carton in passing the angular rollers 37, as illustrated in Fig. 5; this view also particularly shows how the end or flap-opener 43 enters between the inner and outer flaps.

Referring to Fig. 6, which illustrates carrying roller 42, Fig. 31 is an enlarged view of this roller showing particularly its driving mechanism with reference to shaft 25, whereby this pulley is loose in one direction on said shaft and free to operate faster than the shaft in the other direction; Fig. 32 is an end view in elevation of the driving mechanism for roller 42, with the end or flange removed; Fig. 33 is a fragmentary plan view of the appliance shown in Fig. 10, particularly showing the paste roller, the paste disc and appliance for raising and lowering the same. Fig. 34 is an enlarged view of the pasting disc and its mountings with relation to the paste-roller and its mountings, whereby a relatively fixed adjusted position may be maintained between said two rollers during the movement of the pasting disc into and out of pasting position.

Similar numerals refer to similar parts throughout the several views.

1 is the initial feed belt upon which is placed a carton upon entering the machine. This belt is preferably a plane conveyor belt without pusher members. 2 is a guide rail on one side of the machine, having a protruding member 3 to force the entering carton away from said guide rail 2 towards the opposite guide rail 4, which latter guide rail is provided with a projection 5 for the reception of a corner of the carton to stop and hold the same. 6 is a pusher member operated by

lever 7 and cam 8 in timed relation with carrier belt 9 and pushers 10 thereon.

Referring particularly now to the main driving mechanism, 11 is a source of power, in the case shown an electric motor controlled by a manually operated on-and-off switch 12. Motor 11, by means of sprocket 13 and sprocket-belt 14 operating thereon, operates sprocket 15 on rear shaft 16. On shaft 16 are two sprockets 17 and 18 operating carrier-belt 9 upon which it is carried.

Carrier belt 9 is carried over sprockets 23 and 24 on shaft 25, and on shaft 25 is another sprocket 26 operating chain-belt 27, which belt operates sprocket 28 secured to shaft 29.

On main shaft 29 is secured main drive pulley 19 which drives initial feed belt 1. Sprocket 30 is secured to main shaft 29 upon which runs sprocket chain 31, which chain drives sprocket 32 which sprocket is secured to shaft 33 upon which shaft is secured bevelled-gear 34; this gear drives conjugate bevelled gear 35 operating shaft 36. On this shaft 36 is secured cam 8 for operating pusher-member 6.

Between initial feed belt 1 and the flap-opening device and conveyor pertaining to the same, is a mechanism for supporting the carton by its edges in a limited measure to assist in the entrance of the flap-opening mechanism, and consists of a series of angular rollers 37 particularly illustrated in Fig. 6. These rollers 37 are loose running on studs 38 provided with heads to hold said rollers thereon, assembled in frame 39, which frame is supported by support 40 attached to the main frame 41.

On shaft 25 is located a carrying-pulley 42, preferably rubber covered to prevent slippage, for engaging the carton upon its entrance upon the same to continue its movement beyond its range of operation so that the carton will be within the sphere of the pusher-member 10 on carrier belt 9.

I would like to call attention to the fact that carrier-pulley 42 as shown in the drawings ordinarily as driven by shaft 25, travels at a less peripheral speed than belt 1. In order that this pulley 42 shall not be a drag or brake on the rapid and continuous operation of the cartons over the same—as it was only put in as an assisting member in case of a lag—it is provided with ratchet driving means as shown in Figs. 31 and 32, in order that they may speed ahead of the speed of the shaft 25.

I will now describe the method and apparatus for opening the bottom flaps out into the horizontal.

The angular rollers 37 heretofore described are placed at an angle with reference to the horizontal, to a limited extent; in practice it has been found that these rollers depressed at an angle of about 15° are satisfactory, permitting a sufficient depression of the flaps for the entering end of flap-opener 43. At this point, pusher 10 on the carrier belt is in contact with the carton, pushing the same against supplemental flap-opener 44¹ and flap-opener 44. Flap-opener 44¹ and flap-opener 44 are both secured to the flap-opener 43 and are not adjustable. The element 44¹ first encounters the out-turning flap near its edge and throws it outward to assist the flap-opener 44; as the carton progresses the end of flap-opener 43 continues to enter between the outer and inner bottom flaps and supports the contents of the carton, below which flap-opener 43 is a space for permitting the flap to swing outward, and is assisted or controlled in this movement by flap-

openers 44. These openers 44 control the opening of the flap out into the horizontal, or parallel with the face of the inner flaps, when they discharge the open flap onto the main grid table 45. End-opener 43, flap opener 44 and main grid table 45 are all relatively stationary with reference to the main frame 41, and are preferably supported thereby.

When it is desired to avoid applying paste to the outwardly turned flaps, and the paste roller 10 is built up to cover more than the surface of the inner flaps, guard plates 46 are secured to main frame 58 and chain-track 48 to conduct the open flaps over the grid table openings and protect the said flaps from the paste-applying rollers. It 15 is preferable to have one on each side of the machine and of sufficient size to cover the table from the limit of pasting of the inner flaps outward. These guard plates are adjustable and removable, and they are removed when it is desired 20 to paste both outer and inner flaps. Guard plates 46 are preferably adjustably secured as shown by securing bolts to main frame 58 and chain-track 48 by bolt 47.

Main grid-table 45 is preferably constructed as 25 follows:

To permit the paste rollers to operate through said table and at the same time support the contents of the carton, slots 50 are provided within the range both lengthwise and endwise of the 30 operation of the paste rollers. These slots extend from the paste rollers in each direction for a sufficient space to clear the paste rollers in their maximum operation through said slots. Before reaching the slots the table may be plane and 35 flap-opener 43 form a continuation thereof and in width extended to receive the opened flaps from the flap-opener 44, thus being a plane table and is a support for the entire width of the carton and 40 opened flaps.

After passing the slots the table consists of a series of tracks 52 upon which the non-pasted portion of the carton flaps, either inner or outer, may ride without smearing paste. This extends 45 from the grid to closing of the outer flaps.

In the construction and operation of the grid table within the range of the slots in the machine illustrated, I have found in practice that narrow strips, say $\frac{1}{8}$ of an inch wide, were sufficient to support the contents of the carton and prevent 50 a smearing of the paste, the openings being about $\frac{3}{4}$ of an inch, and the paste-rollers having an operating width of substantially $\frac{1}{8}$ of an inch, in which operation no smearing occurred. After the bottom flap passes the slots it is closed by 55 flap-closer 53 and enters upon an intermediate conveyor 54; these strips are supported on one end on flap-opener 43, and on the other end on shaft 45.

Top opening and closing device

Returning now to the entrance of the carton to the under flap opening device, I will describe the top opening device which acts simultaneously with the under flap-opening device.

At this point, the carton is in the machine with its top flaps, inner and outer, standing up or in line in the side walls. It is desired to close the inner flaps, or those at the front and rear ends of the carton, and this is done by the first or entering flap being guided down by the guiding member 55, and the rear or last inner flap is brought down by revolving arm 56. Guiding member 55 is secured to cross-member 57, supported on upper adjustable frame 58. On guiding member 55

is a bearing for supporting-shaft 59 upon which is secured revolving arm 56. On shaft 59 is sprocket 60 driven by sprocket-chain 61, which chain is driven by sprocket 62 on shaft 70, said 5 shaft being driven indirectly by rear shaft 16.

The side upper flaps, which are received in a standing position, are engaged by top flap-openers 64 and turned outwardly and down into the horizontal, or the plane of the inner flap when 10 folded ready to go under the top grid 65. The top flap openers 64 are secured to the upper adjustable frame 58, likewise the top grid 65 is secured to the same frame.

The top grid 65 is similar to the bottom grid 15 within the range of the slots, the revolving arm 56 holding the inner flap down until it engages under the pusher-member 55 and the top grid to which member 55 is attached. The construction of the top grid is similar to that of the 20 bottom grid 45.

Attached to the top grid is a strip 67, which I might call a retainer strip for retaining the inner flap closed until engaged by the outer flaps after the pasting. This member 67 is reduced at 25 its end to facilitate the closing of the outer flaps, as shown at 68. 69 are the top flap closers secured to the upper adjustable frame. At about the end of the strip 67 and the top plate closer 69 is the point of entry of the carton under the 30 intermediate conveyer, as suggested in the bottom closing device.

Pasting mechanism

I might here describe the construction of my 35 pasting rolls, which are adjustable and preferably built up to accommodate the work in hand.

In the construction of my rolls I use a shaft 70, in length preferably the full width of the possible requirements for pasting, including inner and outer flaps. On this shaft I build up 40 my pasting rolls which consists of pasting discs 71. I find it preferable to have a key the whole length of the shaft, or a spline, or some other means to prevent the various elements from 45 rotating thereon. Paste discs 71 are separated by separators 72, of less diameter than the pasting discs, and preferably of slightly greater thickness than that of the grid strips 45, thereby properly spacing the pasting discs to register with the 50 slots 50. In the middle of this paste-roller I have found it desirable on some occasions to have a wide pasting disc to insure the pasting of the inner flaps sufficiently to cause the engagement 55 of the edge of the outer turned flaps. I clamp the aggregation together by any well-known means, such as a nut and collar on each end of the shaft with the proper spacing members. The relative position of the disc paste roller, or the 60 discs thereon, with relation to the face of the grid is such as to permit the paste-discs to protrude through the slots 50 of said grid for about $\frac{1}{4}$ of an inch. This is adjustable by means of the support for the roller which is also adjustable and operable to skip, and which will be described later. (See Fig. 10.)

73 is a paste roller located at the end of the adhesive pot 78, transmitting paste from the bottom of said pot downwardly by its periphery, transmitting the paste to the pasting discs 71, 70 and is mounted on shaft 74 which shaft 74 is driven by main shaft 16 by intermediate means. On shaft 74 is mounted gear 75, meshing with gear 76 secured to shaft 70 and drives the same. 78 is the adhesive pot, on each end of which are 75 forks 79 for supporting the pot, and which are

mounted on shaft 74 by means of bearings 80, one on each end. See Fig. 7, and Fig. 34, which latter figure is the same for prime and un-prime numerals.

The pot is movable with reference to bearings 80, and is adjusted by means of adjusting screws 81, whereby a thicker or a thinner layer of paste may be supplied to the paster roll 73.

It is desirable that pasting roller 73 and pasting disc 71 have the same peripheral speed and 10 operate through the same direction, whereby the paste is laid on from the pasting roller 73 to the pasting disc 71 without friction. I would like to remark here that it is preferable to have the peripheral speed of these two peripheries the 15 same as that of the travel of the carton which they are pasting, in order that there may be no scraping action.

It is desirable that the relative position of 20 paste-roller 73 and pasting disc 71 be definitely maintained in an adjusted position; to that end, connecting links 90 are provided, said links having adjusting means for adjusting said discs to 25 said roller by means of adjusting bearing therein 91 in which operates the shaft 74 of the pasting roller. On the other end of the link 90 is a bearing for shaft 70 of the pasting disc, the adjustment being made by means of screw 93 operating against sliding bearing 91.

On shaft 77 is single cam 84 (see Fig. 18) and 30 operates lever 86 by means of roller 85, which lever 86 operates the lifting of the pasting discs 71 by means of link 87 operating from one end of the lever, said lever being fulcrumed at 88, and the link at the other end being formed as a 35 bearing 89 for shaft 70 containing the pasting disc.

In the top pasting mechanism and adjustment means, cam, etc., prime numbers are given to 40 compare with the lower pasting members to facilitate a rapid understanding of the parts, the prime numbers being the upper members involved, which will now be set forth.

73¹ is the upper paste roller. 78¹ is the upper adhesive pot. 79¹ are forks on said pot which are 45 mounted on shaft 74¹ by means of bearing 80¹, one on each end, and is adjusted by means of screws 81¹. 71¹ are the upper pasting discs. 90¹ is the upper connecting link, and 91¹ the adjusting bearing which operates on shaft 74¹. 89¹ is 50 a sliding bearing on shaft 70 for lever 87.

I wish to particularly describe the two single cams, the one used above and the other used below, in the pasting operation; the one above being what I call the male cam, and which is numbered 111, and the bottom, or female cam, numbered 84.

Cam 111 is mounted on shaft 74¹ and is driven in a manner similar to shaft 70, the upper roller 60 being 85¹ operating lever 86¹, as shown particularly in Fig. 10.

Referring to the presser, so-called, 112 is the top presser belt which is pressed downward by angularly positioned rollers 113, which rollers are 65 mounted on spindle shaft 116 having collars 117, which may consist of cotter-pins and washers, said shaft being bent and operating in bearing 118 and provided with cranks 119 and means for maintaining a pressure on said cranks, as shown, 70 a spring 115. The maximum movement of shaft 116 in bearings 118 is limited by a stop, or other means not shown, to prevent a falling down to an undesirable position.

The above is the most desirable way of pre- 75

venting increased pressure to the central portion of the carton flaps.

In Figs. 11 and 12 a modified form is shown wherein double tapered rollers 120 are used, which gives the desired pressure on the central portion of top presser belts 112. One disadvantage of this modified means is that in irregular cartons adjustability and uniformity of pressure is somewhat varied; but for regular work it has been found satisfactory.

Double tapered rollers 120 are supported in bearings 121, which are supported by springs 122, said springs being secured to top main-frame 114.

Referring now to the pasting skip mechanism and the modified form thereof (see Figs. 18-25, also Fig. 33), 84 is the female, or bottom, cam to control the skip in the pasting of the bottom flaps, and consists of cam face 123. Cam 84 operates on sleeve 126, said sleeve being operatively secured to shaft 77 by means of sliding key 124 operating in elongated key-way, or slot, 125. This is particularly shown in Figs. 18 and 19. Cam 84 is provided with a circular groove 127 in which operates securing bolt 128. This securing bolt when loosened by hand permits cam 84 to rotate on sleeve 126 to any position within the limits of the circular groove 127, and may be secured in any desired position within said limits by means of bolt 128. This adjustment provides means for shifting the position of the pasting skip on the carton. This is done by hand when the machine is stopped. This sleeve 126 is adjusted longitudinally relative of the shaft 77 by loosening set-screws 129 and moving the sleeve until the proper relative position is had with reference to cam roller 85, which in this particular case is longitudinally stationary, as shown in Fig. 33. This adjustment permits a longer or a shorter engagement of the roller on the high surface of the cam which is the pasting surface of the lower pasting roll. A modification of the longitudinal adjustment cam 84 and roller 85 relatively is shown in Fig. 23, where the roller may be shifted instead of the sleeve on the shaft, 130 being a modified end of lever 86 provided with a slot for permitting an adjustment of the carrying means of said roller 85.

A similar adjustment of cam 111 on sleeve 131 is accomplished by turning said cam on said sleeve and securing the same with set-screw 132, the longitudinal adjustment being accomplished in a manner similar to that described for the cam controlling the lower pasting roll.

In the case of some machines, especially where small lots are to be run and a rapid adjustment of the machine is wanted, it is desirable to have an adjustment of the machine while the same is running. To accomplish this, I have shown a modification of the cam 84, and a similar modification would apply to cam 111, showing means for rotating said cam on its respective sleeve without loosening the set screw. This is done by means shown in Figs. 24 and 25, wherein the cam is provided with an operating collar 132, which collar is relatively stationary with reference to the frame of the machine, excepting as the same may be moved by the adjustment of threaded portion of the handles 133 thereof operating in a fixed member 134 with relation to the frame of the machine. By means of collar 132 cam 84¹¹ may be moved longitudinally with reference to shaft 77. Cam 84¹¹ is provided on each side thereof with spiral grooves 135 in which studs 136 operate, said studs being secured to sleeve 126. In other words, in place of the

circular groove 127, shown in Fig. 18, I use a spiral groove 135, as shown in Fig. 24, which accomplishes the same object. In order to maintain the relative position of cam roller 85, the same is moved longitudinally by means of rod 137 which is adjustable in handle 133 by means of set-screw 138. The rod 137 is provided with a joint 139 to permit the operation of cam-roller 85 without springing rod 137.

It is preferable that cam-roller 85 be mounted with reference to lever 86 in a manner similar to that shown in Fig. 23, by means of member 130, the said roller being movably mounted so that it may slide thereon in order that the adjustment of rod 137 by means of set screw 138 may be accomplished while the machine is running. After a proper setting of the machine, cam roller 85 may be more firmly secured to member 130.

Intermediate transfer element

Between the pasting appliance and the pressing appliance, as heretofore suggested, is located intermediate transfer element, which in the machine shown consists of one roller in the bottom, 94, a rubber covered roller power-driven, and on top a frame 97 which operates loose running rollers 98. Frame 97 is removably mounted, as shown by hinge 102, so that the same may be lifted and the carton removed, if desired. Lower power-driven roller 94 is operated by sprocket 103 mounted on shaft 104, on which shaft is secured said roller 94. Shaft 104 is mounted in bearings on the main frame and is driven by chain 105 from sprocket 106, which latter sprocket is mounted on shaft 16. Thus, after the carton leaves the flap-closing device, it is carried by the transfer element independent of the conveying means in the pasting and folding apparatus, and independent of the conveying means in the sealing apparatus to such a point as may permit entrance into the sealing apparatus. The speed in this transfer element is greater than the speed of either of the other conveying mechanisms.

Presser

In outline, the presser consists of lower presser rolls 107 which support lower belt 108, which has a variable speed control or which is driven by pulley 109 over which it runs, said pulley being secured to shaft 110.

It is desirable that lower belt 108 be driven at a varying speed, according to the requirements for pressing purposes. To that end, adjusting means is provided, such as a variable speed motor, or other means for variable speed drive, not shown, the object being to maintain the cartons in the presser a sufficient length of time to properly seal the same. I might note here that the speed of the presser belt determines the speed of the conveyer to the pasting apparatus to prevent a choking of the machine; thus the speed of the conveyer belt is adjustable with reference to the presser belt and the length of the carton operated upon, so that the net delivery in length of cartons is practically the same passing the pasting rolls and the presser.

Referring to Figs. 13 and 14, it will be noticed that the top presser belt 112 operates under angular positioned rollers 113 and holds down the top flaps of the carton with increasing pressure towards the center of the carton, as may be desired, by the adjustment of the top frame carrying these rollers in an up-and-down posi-

tion, ordinarily the proper average strength required of the springs 115 having been previously determined.

The operation of my invention is as follows:

5 *Feeding of the carton to the flap-unfolding device*

The carton is fed to the machine by a travelling belt, or roller conveyer, or other means, and is checked in its progress by an offset in the path of its transit and positively retained until released from this positive stop. This is accomplished by mechanism timed with the carrier device. The flap-unfolding device begins to operate as the inner bottom flaps are forced over a table for supporting the same and the contents of the carton, the outer bottom flaps being progressively outwardly folded to a point above the surface of the table, so that the inner flaps and outer flaps rest substantially in the same plane, and are in a position to receive an adhesive as may be desired.

20 The outer top flaps with the bottom flaps are simultaneously progressively outwardly folded to a point below the surface of a guide, so that the inner top flaps and outer top flaps rest substantially in the same plane and are in a position to receive adhesive as may be desired.

30 *Pasting appliance*

35 The table upon which the inner and outer flaps rest in the flight through the machine is provided with slots, said slots being in position and of length to accommodate the pasting discs which protrude through said slots. Ordinarily, it is not desirable to apply adhesive to the out-turned flaps, and to prevent such application of adhesive the table is modified to provide a shield to prevent the flap from contacting with the 40 pasting disc, particularly shown in Fig. 27.

45 In the application of adhesive to inner and outer flaps, advantage may be taken of the character of the construction of the pasting discs to build up the same as a single unit of the number of parallel adhesive applying discs as may be necessary to coat the surface of the flaps desired. When the paste-roller is built up of a sufficient number of discs to coat only the inner flaps, discs or guards under the lower bottom 50 flaps and over the top flaps may be omitted; either way of adjusting the machine is found to be perfectly satisfactory.

55 *Skip-applying mechanism*

60 Heretofore much difficulty has been experienced in adjusting the skipping mechanism for the paste-roll by means of a plurality of cams in what is known as the "cut-and-try" process; the applicant, realizing the crudeness of the primitive way of making this adjustment, has set forth herein an improvement, a single cam provided with a rider element which accomplishes the desired result in a simpler way, and is provided with adjustable means so that an adjustment is 65 possible while the machine is running, and the result of the adjustment may be observed; means is shown as providing an adjustment that may be made as to the width of the skip, as well as to the relative position of the skip.

70 Describing my improved means for causing the pasting rolls to skip when pasting, the single cam when brought down to the limit of the point and a space below the point, will permit a continuous pasting; the width of the point from the 75 point up determines a short and, as you advance

the roller, a longer continuation of the non-pasting until the extreme limit of the cam is reached which, theoretically, may extend entirely around the shaft, which in that position will cause the pasting mechanism entirely to refrain from pasting.

5 The above is for the top member; the bottom member is the reverse, that is, instead of there being a hump there is a depression, and as the roller drops into the depression at the point a slight abstraction of the pasting mechanism occurs, and as this depression widens as it proceeds endwise of the shaft this extends, permitting the pasting mechanism to be withdrawn a greater distance until we reach a point, theoretically, when 15 we can go entirely around the shaft on the depression, at which point no pasting occurs.

In the drawings as shown, the limits above described are not considered necessary, and the maximum withdrawal of the pasting mechanism 20 is shown as only one of half-time action, or 180°, as that is considered to be a practical unit.

25 In the specification and claims, when I use the terms "paste", or "pasting", "glue" or "gluing"; "adhesive", or "adhesives", I use them synonymously.

Having thus described my invention, what I claim and desire to secure by Letters Patent is:

1. A machine for sealing filled cartons comprising means for receiving a carton resting on 30 its bottom flaps with the bottom flaps closed but unsealed, means for opening the outside bottom flaps from closed position to a position substantially horizontal to expose the inner surfaces of said flaps, means for engaging the inner bottom 35 flaps for supporting the carton during such operation, means for applying adhesive to said inner bottom flaps and means for thereafter closing said outside bottom flaps against the inner bottom flaps to thereby seal the bottom of the carton 40 and means for supporting the inner bottom flaps after coating with adhesive to the point of the closing of the outer bottom flaps.

2. In a box-sealing machine, in combination, means to successively advance boxes provided 45 with bottom side and bottom end flaps, means for applying adhesive to the said end flaps, means for opening the side flaps above said applying means and guard plates between said outer flaps and said adhesive applying means to prevent adhesive being applied to said outer flaps, and means for closing the side flaps after the adhesive has been applied to said inner flaps.

3. In a gluing and sealing machine for shipping cases, or the like, a supporting structure 55 having means for moving shipping cases therethrough, a glue-applying device positioned to apply glue to the flaps of said shipping cases while passing through said machine, and cam means for moving said glue-applying device whereby the 60 same may be placed out of glue applying position at desired position of the shipping cases while passing said cam means, including a cam rotatively secured to a cam-shaft, said cam increasing in extreme operative surface in direction longitudinal of said shaft and a cam operated member adjustable longitudinally relatively to said cam secured to a shaft which operates the movement of said glue-applying device, said members being 65 relatively adjustable with reference to each other and means for relatively adjusting said cam and said cam-operated member while said machine is in operation, consisting of means for relatively positioning said cam with reference to said cam- 70 75 80 85 90 95 98

operated member longitudinally in direction of their respective shafts.

4. In a carton closing machine, the combination of a support for said carton having its carton engaging face at least as wide as the width of the carton and an opposed carton-pressing member having its face contacting with the middle of the carton at a greater pressure, said face exerting a diminishing pressure from the center of the carton outwardly to a point of no pressure on the face of the carton near its edges whereby the side edges of the carton forming the fold lines of the flap will not be subjected to pressure.

5. In a carton-sealing machine, a pair of belts spaced apart to receive cartons between them with their gummed flaps engaged by the faces of the belts, said belts being wider than the carton, and means for applying increasing pressure upon one of said belts from the edge thereof towards the center exterior of the carton whereby the cartons may have exerted on the center line thereof an extreme pressure reducing towards the edges of the carton.

6. In a package-sealing machine, the combination of a guide-way, of a conveying device to convey packages along the guideway, means to fold the flaps of the packages, and a presser situated in line with said guide-way, said presser having means independent of the conveying means to feed packages positively therethrough, a transfer conveyor situated between said presser and said conveying device of length greater than the packages whereby the packages are relieved from the first mentioned conveying device before entering said pressing device, thus permitting an independent movement of the package at an increased speed over the conveying device and of the presser feeding means, and means for maintaining the top carton flaps closed while on said transfer conveyer, consisting of rolls mounted in a movable frame that may be moved out of the way when desired to remove cartons from said transfer conveyer.

7. A machine for sealing filled cartons comprising means for receiving a carton resting on its bottom flaps with its bottom flaps closed but unsealed, means for opening the outside bottom flaps from closed position to a position substantially horizontal to expose the inner surfaces of said flaps, means for engaging the inner bottom flaps for supporting the carton during such operation, means for applying adhesive to said inner bottom flaps and said outside bottom flaps, means for supporting the inner bottom flaps after coating with adhesive to the point of the closing of the outer bottom flaps, and means for thereafter closing said outside bottom flaps against the inner bottom flaps to thereby seal the bottom of the carton.

8. A machine for sealing filled cartons comprising means for receiving a carton resting on its bottom flaps, means for opening the outside top flaps to a position below the horizontal to expose the inner surfaces of said flaps, thus exposing the outside surfaces of the inner flaps, means for applying adhesive to said inner top flaps, a guard means for preventing adhesive being applied to said outer top flaps, means for thereafter closing said outside top flaps against the inner top flaps to thereby seal the top of the carton.

9. In a box-sealing machine, in combination, means to successively advance boxes provided with top side and top end flaps, means for applying adhesive to the end flaps while in closed position, means for opening the side flaps, means for deflecting the same below said applying means out of contact of the said adhesive-applying means, and means for closing the side flaps after the adhesive has been applied.

10. In a box-sealing machine, the combination of means adapted to successively advance boxes provided with bottom side and bottom end flaps, means for applying adhesive to the end flaps, stationary means for opening the side flaps, means for deflecting the same above the applying means out of contact of the said adhesive-applying means, and stationary means for closing the side flaps after the adhesive has been applied.

11. In a gluing machine for shipping cases, or the like, a supporting structure having means for moving shipping cases therethrough, a glue-applying device positioned to apply glue to the flaps of said shipping cases while passing through said machine and cam means for moving said glue-applying device whereby the same may be placed out of glue-applying position at desired positions of the shipping case while passing, said cam means including a cam rotatively adjustable with reference to a cam shaft upon which it is placed whereby the glue-applying device may be out of glue-applying position at a different position of the interval with reference to the shipping case, said cam increasing in extreme operative surface in direction longitudinal of said shaft, and a cam-operative member adjustable longitudinally relative to said cam and operated thereby operating a shaft which operates the movement of said glue-applying device and means for relatively adjusting said cam and said cam-operated member while said machine is in operation, consisting of means for relatively positioning said cam with reference to said cam-operated member longitudinally in direction of their respective shafts.

12. In a gluing machine for shipping cases, or the like, a supporting structure having means for moving shipping cases therethrough, a glue-applying device positioned to apply glue to the flaps of said shipping cases while passing through said machine, and cam means for moving said glue-applying device whereby the same may be placed out of glue applying position at desired positions of the shipping case while passing, said cam means including a cam rotatively adjustable with reference to a cam shaft upon which it is placed whereby the glue-applying device may be out of glue-applying position at a different position of the interval with reference to the shipping case, means for rotatively adjusting said cam while the same is in motion whereby the said interval is changed in relative position to the shipping case, and a cam-operated member operating a shaft which controls the movement of said glue-applying device.

13. In a carton-sealing machine, a pair of belts spaced apart to receive cartons between them with their gummed flaps engaged by the belts, means for applying increasing pressure upon one of the said belts from the edge thereof towards the center on one edge, and means for applying increasing pressure upon the same belt from the other edge thereof towards the center, whereby the carton may have exerted upon its end independent yieldable pressure on the two sides thereof.

14. In a machine for sealing filled cartons comprising means for receiving a carton resting on its bottom flaps, means for opening the out-

- side top flaps to a position substantially horizontal and beyond the same, means for closing the inner top flaps whereby the paste-receiving surfaces thereof are substantially in a horizontal 5 plane, means for applying adhesive to said inner top flaps, means for deflecting the outer top flaps below the horizontal to protect the same from the adhesive-applying means and means for thereafter closing said outer top flaps against 10 the inner top flaps, thereby sealing the top of the carton.
15. A machine for sealing filled cartons comprising means for receiving a carton resting on its bottom flaps, means for opening the outside 15 top flaps to a position substantially horizontal to expose the inner surfaces of said flaps, means for folding the inner flaps to a position substantially horizontal to expose the outer surface of said flaps, whereby the surfaces of the said outer and 20 inner flaps are substantially in the same plane, means for applying adhesive to said inner top flaps and said outer top flaps consisting of discs provided with intervals between the same and positioned with reference to the inner flaps, so that 25 a disc applies adhesive to the central portion of said flaps to receive the edges of the in-turned outside flaps, and intervals alternating with lanes of paste are applied outwardly from the same longitudinally as the carton is fed through the 30 machine, and means for thereafter closing the said outside top flaps against the inner top flaps to thereby seal the top of the carton.
16. In a box-sealing machine in combination, means to successively advance boxes provided 35 with top side and top end flaps, means for applying adhesive to the end flaps while in closed position, means for opening the side flaps below said applying means out of contact of the said adhesive-applying means consisting of a guard between said flaps and said adhesive-applying means, and means for closing said flaps after the adhesive has been applied.
17. A machine for sealing filled cartons comprising means for receiving a carton resting on 40 its bottom flaps with its bottom flaps closed but unsealed, means for opening the outside bottom flaps from closed position to a position substantially horizontal to expose the inner surface of said flaps, means for engaging the inner bottom 45 flaps for supporting the carton during such operation, means for opening the outside top flaps to a position substantially horizontal to expose the inner surface thereof, means to close the inner top flaps to a position substantially horizontal to expose the outer surface thereof, thus exposing the outer surfaces of the inner flaps and the inside surfaces of the outer flaps, a plurality of means for simultaneously applying adhesive to 50 said inner top flaps, outer top flaps, inner bottom flaps and outer bottom flaps consisting of a plurality of adhesive applying means working simultaneously, and means for thereafter closing said outer top flaps and the said outer bottom flaps against the inner flaps consisting of top and 55 bottom flap-closing means, thereby sealing the bottom and top of the carton.
18. A machine for sealing filled cartons comprising means for receiving a carton resting on its bottom flaps, with its bottom flaps closed but 60 unsealed, means for opening the outside bottom flaps from closed position to a position substantially horizontal to expose the inner surface of said flaps, means for engaging the inner bottom flaps for supporting the carton during such operation, means for opening the outside top flaps 65
- to a position substantially horizontal to expose the inner surface thereof, means to close the inner top flaps to a position substantially horizontal to expose the outer surface thereof, thus exposing the outside surfaces of the inner flaps and the inside surfaces of the outer flaps, a plurality of means for simultaneously applying adhesive to 70 said inner top flaps, and inner bottom flaps consisting of a plurality of adhesive-applying means working simultaneously, and means for thereafter closing said outer top flaps and the said outer bottom flaps against the inner flaps consisting of top and bottom flap-closing means, thereby sealing the bottom and top of the carton.
19. In a gluing machine for shipping cases, or 75 the like, a supporting structure having means for moving the shipping cases therethrough, a gluing device positioned to apply glue to the flaps of said shipping cases while passing through the said machine, and cam means for moving said glue-applying device whereby the same may be placed out of glue-applying position at desired 80 positions of the shipping cases while passing, said cam increasing in extreme operative surface in direction longitudinal of said shaft upon which 85 it is mounted, whereby the extent of the non-glue applying interval may be adjusted, and a cam-operated member adjustable longitudinally relative to said cam and operated thereby operating a shaft which operates the movement of 90 said glue-applying device, the position of said cam-operated device in relation to said cam determining the extent of the non-glue applying 95 interval.
20. In a box-sealing device provided with runway and means for conveying boxes therethrough, 100 consisting of a conveyer operating in conjunction with said runway, a flap-closing device operating to close the flaps of cartons while being conveyed by said conveyer, an intermediate convey- 105 ing means for receiving the cartons with their respective flaps folded after having passed the folding appliance, operating at a greater speed than the first mentioned conveyer, whereby the 110 cartons are taken away from the said first mentioned conveyer and delivers said cartons to a pressing device, said intermediate conveyer consisting of a tractive element, upon which said cartons rest, operating at a speed to convey the 115 cartons faster than the said first mentioned conveyer, and means for keeping the top flaps closed after having passed said closing device consisting of a movable pressing means whereby the 120 cartons may be removed from the intermediate conveyer, if desired, said movable pressing means 125 consisting of rolls mounted in a movable frame that may be moved out of the way when desired to remove cartons from said transfer conveyer.
21. In a carton-sealing machine provided with flap-opening means, an initial flap-opener comprising a horizontal angular conveying support 130 consisting of rollers arranged horizontally inclined downwardly towards the center to support the outer flaps of the carton to permit the edges to slightly open to permit the entrance of means 135 to continue the opening of said flaps and positive means for progressing said carton to said initial flap opener consisting of a power-operated roller operating under the carton as the same passes over.
22. In a carton-sealing machine provided with flap-opening means, an initial flap-opener comprising a horizontal angular conveying support 140 consisting of rollers arranged horizontally inclined downwardly towards the center to support 145

- the outer flaps of the carton to permit the edges to slightly open to permit the entrance of means to continue the opening of said flaps, and an initial feeding means to said initial opening device, and a final opening device in line with and on the same level with the said initial feeding device and positive means for progressing said carton to said initial flap opener consisting of a power-operated roller operating under the carton as the same passes over.
23. In a carton-sealing machine provided with flap-opening means, an initial flap-opener conveying support comprising a horizontal angular conveying support for the flaps at a definite opened position to permit the entrance of means to continue the opening of said flaps, and an initial feeding means to said initial opening device, and a final opening device in line with and on the same level with the said initial feeding device, said horizontal angular conveying support consisting of a plurality of angular-disposed rollers under each side of the carton to be conveyed combined with power-actuated means for insuring the continual movement of the carton over the said angular conveying support, and means for adjusting the relative position of said plurality of roller elements on each side relatively in order to accommodate cartons of different widths.
30. 24. In a carton-sealing machine provided with flap-opening means, an initial flap-opener comprising a horizontal angular conveying support for the flaps at a definite opened position to permit the entrance of means to continue the opening of said flaps, said initial opener comprising a plurality of roller elements on each side of the carton to support the carton at the maximum at its edge decreasingly towards its center to permit the flaps to slightly open and positioned to receive the carton from a level of the initial feed to the machine and deliver the same at the same level to the final flap-opener and power-actuated means for insuring the continual movement of the carton over the said angular conveying support.
45. 25. In a carton-sealing machine provided with flap-opening means, an initial flap-opener comprising a horizontal angular conveying support consisting of rollers extending inwardly and downwardly from the flap edges to support the outer flap edges of the carton to permit the inner edges to partially open to permit the entrance of means to continue the opening of said flaps, and power driven means upon which said carton rests operating to insure the travel of said carton to said initial flap-opener.
55. 26. In a carton-sealing machine as described in claim 25, said tractor means comprising a resilient covered roller.
60. 27. In a carton-sealing machine as described in claim 25, said tractor means comprising a driving means therefor operated in one direction and loose in the other, whereby said tractor means may travel faster than its driving means.
65. 28. In a carton-sealing machine provided with a flap-opening device, means for applying adhesive to flaps opened in said machine consisting of a plurality of pasting discs operating through a grid-supporting element for said cartons, and means for closing the flaps after the adhesive has been applied.
70. 29. In a carton-sealing machine provided with a flap-opening device, means for applying adhesive to flaps opened in said machine consisting of a plurality of pasting discs operating in con-
- junction with retaining strips to hold the flaps in position while being pasted, and means for closing the flaps after the adhesive has been applied.
30. In a carton-sealing machine provided with flap-opening mechanism and flap-closing mechanism, an adhesive applying mechanism comprising a pasting roll of a plurality of circular pasting surfaces spaced apart to provide non-pasted strips, the centrally located one of said surfaces being broader than the others to ensure the application of adhesive to the inner flaps registering with the edges of the out-turned flaps when turned inward and contacting therewith, and means for supplying said pasting surfaces with adhesive.
35. 31. In a box-sealing machine, the combination of means adapted to advance boxes therethrough, said boxes being provided with bottom side and bottom end flaps, means for relatively positioning the several flaps so that the end flaps are in closed position and the side flaps are open to permit the application of adhesive to said end flaps, means for applying adhesive in parallel lanes having blank spaces between the same to said bottom end flaps while the same are in closed position, means for supporting said bottom end flaps after coating with adhesive to the point of closing of the said side flaps, consisting of means for supporting said flaps intermediate of said pasted lanes of adhesive to prevent smearing thereof, and means for folding said side flaps onto said end flaps.
40. 32. In a package-sealing machine in combination, flap-folding mechanism, package-feeding means, a stop device to prevent packages from being delivered to said flap-folding mechanism, consisting of a permanent fixed stop against which said package contacts, said stop preventing packages from being delivered to said flap-folding mechanism, a conveyer for feeding packages to said flap-folding mechanism and controlling the speed of the package to the flap-folding mechanism, consisting of a plurality of rolls loosely mounted on shafts and a power driven roll operated positively in one direction by the driving mechanism to feed a carton at a speed less than the package-feeding means but loose to exceed said speed on its shaft, and means for releasing said package from said permanent stop operated 50 in timed relation with said conveyer to cause the package to be released from said stop and to enter within the operation of said conveyer at a predetermined position of said conveyer.
45. 33. In a carton-closing machine provided with a flap-closing device, a flap presser comprising means for exerting a pressure upon the central portion of the carton going through the machine in excess of the pressure exerted upon the edge of the carton, consisting of a plurality of inclined rolls mounted on shafts which shafts are resiliently mounted to press downwardly upon the center portion of said carton, whereby the flaps of the carton under said plurality of rolls are pressed by each series of rolls on said shafts independently, and means for conveying said carton through said presser.
55. 34. A pressing member in a carton-closing machine receiving closed cartons from said machine to maintain the flaps closed after the application 60 of adhesive, consisting of means for exerting a maximum pressure along the center line of the carton so being sealed, said pressure diminishing towards the edge of said carton, consisting of two rows of rollers, each roller mounted on a shaft 65
70. 75. of a plurality of pasting discs operating in con-

- independent to move with reference to the other of said rollers, means for maintaining the ends of said rollers near the center of the package depressed to the maximum whereby a maximum pressure for sealing purposes is exerted along the central portion of said carton, and means for passing said carton under said rollers.
35. In a machine for sealing cartons, means for advancing cartons resting on their inner bottom flaps therethrough, means for supporting the inner bottom flaps during the passage of said carton through said machine, consisting of a grid and means for applying adhesive to said inner bottom flaps through said grid, whereby a plurality of lanes of adhesive are applied to said inner bottom flaps while passing through said machine.
36. In a machine for sealing filled cartons, comprising means for receiving a carton resting on its bottom flaps with its bottom flaps closed, means for advancing the carton through the machine, means for folding the outer top carton flaps outwardly to expose the outer surface of the inner top flaps, means for folding inwardly said inner top flaps consisting of a stationary folder for closing the entering top inner flap, whereby said flap is folded into a horizontal position and held there during the gumming of said flap and the folding of the outer flaps thereonto, a closer for forcing the rear of the inner top flap into a position to be encountered by said folder as the carton progresses through the machine, means for driving said flap-folder, including a yielding means whereby the movement of said folder may be stopped when the resistance to the movement exceeds a predetermined amount, means for gumming said inner top flap when held as above in said horizontal position, and means for folding said outer top flaps onto said gummed inner top flaps.
40. 37. In a machine for sealing cartons, means for advancing the cartons resting on their flaps therethrough, means for folding the outer bottom flaps outward into substantially horizontal position, means for supporting the inner bottom flaps during the passage of said carton through said machine, means for supporting the outer bottom flaps consisting of the grid upon which they rest, means for applying adhesive to the out-turned outer bottom flaps through said grid which supports said outer bottom flaps, whereby a plurality of lanes of adhesive are applied to said outer bottom flaps while passing through said machine, and means for thereafter folding said outer bottom flaps onto said inner bottom flaps.
55. 38. In a carton sealing machine, means for advancing cartons therethrough, exposing the top flaps of said carton, means for opening and maintaining the outer top flaps open to expose the outer surface of the inner top flaps, means for applying adhesive to said outer surface of said inner top flaps in parallel lanes having blank spaces without adhesive between said lanes, means for maintaining said inner flaps folded comprising a grid through which the adhesive-applying means works, and means for folding said outer top flaps onto said inner top flaps after said adhesive has been so applied.
39. In a box-sealing machine the combination of means adapted to successively advance boxes provided with top side flaps, top end flaps, bottom side flaps and bottom end flaps, means for applying adhesive to the top and bottom end flaps, stationary means for opening the top and bottom side flaps, means for deflecting said top and bottom side flaps below and above respectively the applying means out of contact of the said adhesive-applying means, and stationary means for closing the side flaps after the adhesive has been applied.
40. In a carton sealing machine comprising a flap-closing device provided with a conveying means for conveying a carton therethrough and a presser operating to maintain a pressure upon the closed flaps of a carton passing therethrough provided with conveying means for conveying cartons passing therethrough, means for adjusting the relative speeds of said two conveying means to accommodate cartons of different lengths passing through said machine.
41. In a carton sealing machine provided with flap-opening mechanism and flap-closing mechanism, an adhesive applying mechanism comprising a roll the surface of which is the paste-applying surface, means for supplying said surface with adhesive consisting of a paste-applying roll transferring paste from a reservoir, means for adjusting the relative position of said two rolls to regulate the distance between the surfaces thereof consisting of mounting the shafts of said rolls in links holding the same together in fixed position, and means for adjusting one of said rolls in said links, changing said fixed position as desired.
42. In a carton-sealing machine provided with means for conveying cartons therethrough, a flap-closing means in said machine for closing flaps while being conveyed by said conveyer, means for retaining the inner top flaps closed in position while the outer top flaps are being folded into closed position, consisting of a contacting element operating centrally with reference to the carton to permit the side flaps to be closed while said element is holding the end flaps closed, said element at its final contacting end being recessed from the inner flaps contacting surface sufficiently to permit the side flaps to enter thereunder.
43. A machine for sealing filled cartons having two outside top flaps comprising means for receiving a carton resting on its bottom flaps, means for opening the outside top flaps, thus exposing the outside surfaces of the inner flaps, means for applying adhesive to said inner top flaps only, and means for thereafter closing each of said two outside top flaps simultaneously against the inner top flaps to thereby seal the top of the carton.

CHARLES H. WILD.
